Filed Feb. 25, 1965, Ser. No. 435,306
12 Claims. (Cl. 330—43)

This invention relates generally to microwave amplifiers, and more particularly relates to a bias arrangement for a linear electron beam microwave amplifier tube operated with a depressed collector potential. As used herein the term bias is intended to mean a D.C. potential applied between any pair of electrodes of an electronic device to establish a desired operating condition.

In microwave amplifiers of the traveling-wave type a stream of electrons traveling from a cathode to a collector electrode is caused to interact with a propagating electromagnetic wave in a manner which amplifies the electromagnetic energy. In order to achieve such interaction the electromagnetic wave is propagated along a slow-wave structure such as a conductive helix wound about the path of the electron stream. The slow-wave structure provides a path of propagation for the electromagnetic wave which is considerably longer than the axial length of the structure, and hence, the traveling wave may be made to effectively propagate at nearly the velocity of the electron stream. Interaction between electrons in the stream and the traveling wave causes velocity modulations and bunching of the stream electrons. The net result may then be a transfer of energy from the electron stream to the wave traveling along the slow-wave structure, resulting in amplification of the traveling wave.

In order to increase efficiency, traveling-wave tubes have been operated with a depressed collector potential, i.e. with the collector electrode biased at a potential significantly lower than the potential of the slow-wave structure. For example, in typical depressed collector operation the collector potential may be in a range essentially from 50% to 70% of the slow-wave structure potential as measured with respect to the cathode.

One prior art arrangement for biasing a traveling-wave tube for depressed collector operation includes a first power supply connected between the cathode and the collector electrode to maintain the collector at a predetermined positive potential with respect to the cathode. A second power supply, providing a voltage of a magnitude greater than that of the first power supply, is connected between the cathode and the slow-wave structure to bias the slow-wave structure positively with respect to the cathode by the desired amount. In this bias arrangement not only are two power supplies required, but in order to prevent damage to the tube, two rapidly acting high voltage switches also must be employed to disconnect the tube from both power supplies in the event of a fault such as arcing.

In a second prior art biasing circuit for a depressed collector traveling-wave tube a first power supply is again connected between the cathode and the collector electrode to bias the collector positively with respect to the cathode, while a second power supply is connected between the collector electrode and the slow-wave structure to bias the collector negatively with respect to the slow-wave structure. For the same relative electrode potentials, a lower voltage second power supply may be used in the second arrangement than in the first arrangement. However, both circuits have the same power delivery requirements, and the second arrangement also re-

quires two power supplies and two high voltage high speed disconnecting switches.

In a third prior art scheme for biasing a traveling-wave tube for depressed collector operation, a first power supply is connected between the cathode and the slow-wave structure to bias the slow-wave structure positively with respect to the cathode, and a power sink is connected between the slow-wave structure and the collector electrode to maintain the collector electrode at the desired negative potential relative to the slow-wave structure. Although the third arrangement employs only one active power source and only one fast acting high voltage disconnecting switch, nevertheless, a high current capacity power sink is required. Moreover, the overall power delivery requirements of the third arrangement are significantly higher than those of the first two arrangements.

Accordingly, it is an object of the present invention to provide a bias arrangement for operating a linear electron beam microwave amplifier with a depressed collector potential which requires only one power supply and only one rapidly acting high voltage disconnecting switch, and which bias arrangement also has relatively low power delivery requirements.

It is a further object of the present invention to provide a bias circuit for a depressed collector electron beam microwave amplifier which eliminates the need for one of the power supplies, operated as either a power source or a power sink, heretofore required.

It is a still further object of the present invention to provide a bias arrangement for a depressed collector microwave amplifier tube, preferably of the traveling-wave type, which is smaller and lighter than comparable bias arrangement of the prior art.

In accordance with the objects set forth above, the bias circuit of the present invention includes a power supply coupled between the cathode and the interaction structure of the electron beam microwave amplifier to be biased for depressed collector operation and a transformer-rectifier arrangement coupled to the power supply. The primary winding of the transformer is coupled between the interaction structure and the collector electrode of the microwave amplifier, while the secondary winding of the transformer and the rectifier are coupled in series across the power supply.

Other and further objects, advantages and characteristic features of the present invention will become readily apparent from the following detailed description of preferred embodiments of the invention when considered in conjunction with the accompanying drawing in which:

FIG. 1 is a schematic circuit diagram illustrating one embodiment of the invention; and

FIG. 2 is a schematic circuit diagram showing another embodiment of the invention.

In FIG. 1 a linear electron beam microwave amplifier tube utilizing a bias arrangement according to the present invention is illustrated as a traveling-wave tube 10 having an electron emitting cathode 12, a slow-wave interaction structure 14, and a collector electrode 16. An input connection 17 is disposed at one end of the interaction structure 14 to apply incoming microwave energy to the device, while an output connection 18 is afforded at the opposite end of the interaction structure to facilitate removal of the amplifier microwave energy. A control grid 20 is interposed between the cathode 12 and the interaction structure 14 in order to control the flow of the electron stream and thereby facilitate pulsed operation of the traveling-wave tube 10. Although any linear electron beam microwave amplifier tube which it is desired to operate with a depressed collector potential may be employed, by way of example the tube 10 may be a 396H traveling-

wave tube manufactured by Hughes Aircraft Company, Microwave Tube Division, Los Angeles, California.

In the bias circuit of the present invention a power supply 22, which may be any regulated power supply having appropriate voltage and current ratings, is connected between the cathode 12 and the interaction structure 14, with the positive terminal of the power supply connected to the structure 14 and the negative terminal connected to the cathode 12. The positive terminal of the power supply 22 may also be connected to a level of reference potential designated as ground in FIG. 1. When the aforementioned exemplary traveling-wave tube is employed, a power supply 22 may be selected which provides a D.C. output voltage E_{bb} of 21.5 kv. at a current of 4.78 amps peak and 47.8 ma. average.

The additional power source or sink required by prior art bias circuits is replaced in the circuit of the present invention by a transformer-diode arrangement. This arrangement includes a pulse transformer 24 having a primary winding 26 and a secondary winding 28, the phase relationship between signals in the primary winding 26 and the secondary winding 28 being indicated in the conventional manner by the dots adjacent the transformer windings. The primary winding 26 is connected between the collector electrode 16 and ground; while the secondary winding 28 is connected in series with a unidirectionally conductive device, illustrated as a diode rectifier 30, between the negative terminal of the power supply 22 and ground. The diode rectifier 30, which should have a peak inverse voltage rating sufficient to withstand the power supply voltage E_{bb} , is connected in such polarity that its cathode faces the positive terminal of the power supply 22 while its anode faces the negative power supply terminal. When used with the aforescribed exemplary traveling-wave tube and power supply, the unidirectionally conductive device 30 may be a diode bank comprising 55 units of Hughes HM2G diodes connected in series.

The pulse transformer 24 should provide a large excitation, or open circuit, inductance in its primary winding 26, and should have an effective ratio of secondary turns N_s to primary turns N_p given by:

$$\frac{N_s}{N_p} = \frac{E_{bb} + E_d}{E_p} \quad (1)$$

where E_{bb} represents the voltage provided by the power supply 22, E_d represents the voltage across the diode 30 when the diode is conductive, and E_p represents the voltage across the primary winding 26 which is equal to the desired voltage between the interaction structure 14 and the collector electrode 16. When the aforescribed exemplary traveling-wave tube and power supply are employed, the transformer 24 may be a pulse transformer designed to operate with a primary voltage E_p of 8.5 kv. at a current of 4.8 amps peak for a pulse duration of 40 microseconds.

In order to permit pulsed operation of the traveling-wave tube 10, a grid modulator 32 may be connected between the control grid 20 and the cathode 12 of the tube 10. The grid modulator 32 may comprise a pulse generator which, for the aforementioned exemplary traveling-wave tube and circuit components, provides at its output terminal connected to the grid 20 a quiescent voltage level of -21.7 kv. with respect to ground and a voltage pulse at a level of -21.1 kv. relative to ground for a duration of 40 microseconds. In the circuit of FIG. 1 the collector current of the traveling-wave tube 10 (which also flows through the primary winding 26 of the transformer 24) is designated I_c , the current flowing to the interaction structure 14 is denoted I_h , and the current flowing through the secondary winding 28 and the diode 30 is designated I_s .

In the operation of the circuit of FIG. 1, assume that initially the grid modulator 32 biases the control grid 20 negatively with respect to the cathode 12 by a sufficient amount (around 200 volts for the aforementioned

exemplary traveling-wave tube) to block the flow of electrons. At this time the collector 16 resides at essentially ground potential; and the interaction structure current I_h , the collector current I_c and the transformer secondary current I_s are all negligible. The power supply 22 biases the cathode 12 negatively with respect to the interaction structure 14 by an amount E_{bb} and also establishes a reverse bias across the diode 30.

When the grid modulator 32 provides an output pulse which biases the control grid 20 positively with respect to the cathode 12 by the desired amount (around 400 volts for the aforementioned exemplary traveling-wave tube), electrons leaving the cathode 12 are accelerated toward the interaction structure 14 and the collector 16 by the potential $+E_{bb}$. Thus, an electron beam is provided along the structure 14, and interaction between microwaves traveling along the structure 14 and the electron beam takes place in the conventional manner to amplify the traveling microwaves. Most of the beam electrons pass through the interaction structure 14 and impinge upon the collector electrode 16, causing a current I_c to flow from the positive terminal of the power supply 22 through the primary winding 26 to the collector 16. Some of the beam electrons are intercepted by the interaction structure 14, and a smaller current I_h flows from the positive terminal of the power supply 22 to the structure 14.

Since the diode 30 is reverse biased, the current flow through the secondary winding 28 of the transformer 24 is negligible, and the secondary winding 28 exhibits an essentially infinite impedance. This high secondary load impedance is reflected into the primary winding 26 where it appears in shunt with the excitation inductance of the primary winding. Since the primary winding excitation inductance is large, a significant potential drop appears across the primary winding 26 due to the flow of collector current I_c . The potential at the collector electrode 16 is thus reduced to a value substantially below that of the interaction structure 14, thereby facilitating depressed collector operation of the traveling-wave tube 10.

For a transformer 24 designed with a turns ratio according to Equation 1, when the voltage across the primary winding 26 exceeds the design potential E_p , a sufficient potential is established across the secondary winding 28 to forward bias the diode 30. Current flow of a magnitude

$$I_s = \frac{N_p}{N_s} I_c$$

thus commences in the secondary winding 28. The current I_s flows in a direction which reduces the net current leaving the power supply 22, thereby conserving power which otherwise would have been dissipated in the power sink if a prior art bias arrangement were employed.

The flow of secondary current I_s causes the impedance of the secondary winding 28 to decrease substantially. If the secondary load impedance reflected into the primary winding 26 is sufficiently low to allow the voltage across the primary winding 26 to drop below the design value, the voltage across the secondary winding 28 will decrease sufficiently to again reverse bias the diode 30. The flow of secondary current I_s ceases, increasing the impedance of the secondary winding 28 to a value sufficient to restore the desired design voltage E_p across the primary winding 26. Thus, a substantially constant voltage E_p of a magnitude determined by Equation 1 is maintained between the interaction structure 14 and the collector electrode 16 so that the collector electrode 16 may be biased to the desired depressed potential. It should be apparent from Equation 1 that the constancy of the voltage E_p is a function of the regulation of the power supply voltage E_{bb} , the forward voltage of the diode 30, and the regulation of the transformer 24.

The depressed collector microwave tube bias arrangement illustrated in FIG. 2 is similar to the arrangement of FIG. 1, and respective components of the circuit of FIG. 2 which are the same as those of the circuit of FIG. 1 are designated by the same respective reference numerals as their counterpart components. However, in the circuit of FIG. 2 a nongridded traveling-wave tube 10', such as a nongridded version of the aforementioned Hughes 396H traveling-wave tube, is employed. Also, in the arrangement of FIG. 2, a modulator switch tube 34 (which replaces the grid modulator 32 of FIG. 1) is connected between the cathode 12 and the negative terminal of the power supply 22.

As long as the modulator switch 34 is open (nonconductive) the cathode 12 is effectively disconnected from the power supply 22. When it is desired to pulse the traveling-wave tube 10', the modulator switch 34 is closed for the desired pulse duration to connect the negative terminal of the power supply 22 to the cathode 12. An electron beam is thus caused to flow from the cathode 12 to the collector 16, resulting in the desired operation of the traveling-wave tube and its biasing circuitry in the same manner as discussed above with respect to FIG. 1.

From the foregoing, it will be apparent that the circuits of FIGS. 1 and 2 provide simple and compact bias arrangements for depressed collector microwave tubes which afford substantial cost savings due to the elimination of one power supply and one disconnecting switch from prior art arrangements. Moreover, additional cost savings are realized as a result of power conservation during operation of the circuits of the invention.

It should also be apparent that while the present invention has been illustrated and described with specific reference to pulse modulated traveling-wave tubes, bias arrangements according to the invention may be employed in conjunction with any linear electron beam microwave amplifier operating with a depressed collector potential. In addition, although the transformer 24 has been described as a pulse transformer, an audio transformer would be used if the tube 10 is to be amplitude modulated at voice frequencies; or the transformer 24 could be replaced with a D.C.-to-D.C. converter if the tube were operated on a continuous wave basis.

Thus, although the invention has been shown and described with reference to particular embodiments, various changes and modifications obvious to a person skilled in the art to which the invention pertains are deemed to lie within the purview of the invention.

What is claimed is:

1. A bias arrangement for a linear electron beam microwave amplifier having a cathode, an interaction structure and a collector electrode comprising: a power supply coupled between said cathode and said interaction structure, a transformer having a primary winding and a secondary winding, said primary winding being coupled between said interaction structure and said collector electrode, and a unidirectionally conductive device and said secondary winding being coupled in series across said power supply.

2. A bias arrangement for a linear electron beam microwave amplifier having a cathode, an interaction structure and a collector electrode comprising: power supply means for providing a predetermined voltage between first and second terminals, the positive terminal being coupled to said interaction structure and the negative terminal being coupled to said cathode, a transformer having a primary winding and a secondary winding, said primary winding being coupled between said interaction structure and said collector electrode, and a diode rectifier coupled in series with said secondary winding between said terminals in a manner to provide unidirectional current flow through said secondary winding in a direction toward the positive terminal.

3. A bias arrangement for a linear electron beam

microwave amplifier having a cathode, an interaction structure and a collector electrode comprising: power supply means coupled between said cathode and said interaction structure for providing a predetermined voltage, a transformer having a primary winding and a secondary winding, said primary winding being coupled between said interaction structure and said collector electrode, a diode rectifier device, said diode rectifier device and said secondary winding being coupled in series between said interaction structure and said cathode, said transformer having an effective ratio of secondary turns N_s to primary turns N_p given by

$$\frac{N_s}{N_p} = \frac{E_{bb} + E_d}{E_p}$$

15 where E_{bb} represents said predetermined voltage, E_d represents the voltage across said diode rectifier device when said diode rectifier device is conductive, and E_p represents the desired voltage across said primary winding during operation of said microwave amplifier.

20 4. A circuit for biasing a linear electron beam microwave amplifier having a cathode, an interaction structure and a collector electrode for depressed collector operation comprising: a power supply for providing a predetermined voltage between first and second terminals adapted to be connected directly to said interaction structure and said cathode, respectively; a transformer having a primary winding connected directly between said collector electrode and said interaction structure and having a secondary winding; and a unidirectionally conductive device, said unidirectionally conductive device and said secondary winding being connected in series between said first and second terminals.

25 5. A circuit for biasing a linear electron beam microwave amplifier having a cathode, a control electrode and an interaction structure and a collector electrode for depressed collector operation comprising: a power supply coupled between said cathode and said interaction structure, a transformer having a primary winding and a secondary winding, said primary winding being coupled between said interaction structure and said collector electrode, a unidirectionally conductive device, said unidirectionally conductive device and said secondary winding being coupled in series between said interaction structure and said cathode, and means for applying a control signal between said control electrode and said cathode.

30 6. A circuit for biasing a linear electron beam microwave amplifier having a cathode, an interaction structure and a collector electrode for depressed collector operation comprising: a power supply for providing a predetermined voltage between first and second terminals, said first terminal being coupled to said interaction structure, a transformer having a primary winding and a secondary winding, said primary winding being coupled between said interaction structure and said collector electrode, a unidirectionally conductive device, said unidirectionally conductive device and said secondary winding being coupled in series between said first and second terminals, and a modulator switch tube coupled to said cathode and said second terminal.

35 7. A bias arrangement for a traveling-wave tube comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

40 8. A bias arrangement for a traveling-wave tube comprising: a power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

45 9. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

50 10. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

55 11. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

60 12. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

65 13. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

70 14. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

75 15. A bias arrangement for a traveling-wave tube comprising: power supply means for providing a predetermined voltage between first and second terminals, the positive terminal being coupled to said cathode, a slow-wave structure and a collector electrode comprising: a power supply coupled between said cathode and said slow-wave structure, a transformer having a primary winding and a secondary winding, said primary winding being coupled between said slow-wave structure and said collector electrode, and a unidirectionally conductive device, said unidirectionally conductive device and said secondary winding being coupled in series with said power supply.

structure and the negative terminal being coupled to said cathode, a pulse transformer having a primary winding and a secondary winding, said primary winding having a large excitation inductance and being coupled between said slow-wave structure and said collector electrode, a diode rectifier device coupled in series with said secondary winding between said terminals in a manner to provide unidirectional current flow through said secondary winding in a direction toward the positive terminal, said transformer having an effective ratio of secondary turns N_s to primary turns N_p given by

$$\frac{N_s}{N_p} = \frac{E_{bb} + E_d}{E_p}$$

where E_{bb} represents said predetermined voltage, E_d represents the voltage across said diode rectifier device when said diode rectifier device is conductive, and E_p represents the desired voltage across said primary winding during operation of said traveling-wave tube.

9. A circuit for biasing a traveling-wave tube having a cathode, a control electrode, a slow-wave structure and a collector electrode for depressed collector operation comprising: a power supply connected between said cathode and said slow-wave structure, a pulse transformer having a primary winding and a secondary winding, said primary winding being connected between said slow-wave structure and said collector electrode, a unidirectionally conductive device, said unidirectionally conductive device and said secondary winding being connected in series between said slow-wave structure and said cathode, and means for applying a control pulse between said control electrode and said cathode.

10. A circuit for biasing a traveling-wave tube having a cathode, a slow-wave structure and a collector electrode for depressed collector operation comprising: a power supply for providing a predetermined voltage between first and second terminals, said first terminal being connected to said slow-wave structure, a pulse transformer having a primary winding and a secondary winding, said primary winding being connected between said first terminal and said collector electrode, a unidirectionally conductive device, said unidirectionally conductive device and said secondary winding being connected in series between first and second terminals, and a pulse operated switch tube connected between said cathode and said second terminal.

11. A circuit for biasing a traveling-wave tube having a cathode, a control grid, a slow-wave structure and a collector electrode for depressed collector operation comprising: power supply means for providing a predetermined voltage between first and second terminals, the negative terminal being connected to said slow-wave structure and the positive terminal being connected to said cathode, a pulse transformer having a primary winding and a secondary winding, said primary winding being connected between said first terminal and said collector electrode, a diode rectifier device, said diode rectifier device and said secondary winding being connected in series between said first and second terminals, and a pulse operated switch tube connected between said cathode and said second terminal.

ture and the negative terminal being connected to said cathode, means for applying a control pulse between said control grid and said cathode, a pulse transformer having a primary winding and a secondary winding, said primary winding having a large excitation inductance and being connected between said slow-wave structure and said collector electrode, a diode rectifier device having an anode terminal and a cathode terminal, said diode rectifier device and said secondary winding being connected in series between said first and second terminals with said cathode terminal facing the positive one of said first and second terminals, said transformer having an effective ratio of secondary turns N_s to primary turns N_p given by

$$\frac{N_s}{N_p} = \frac{E_{bb} + E_d}{E_p}$$

where E_{bb} represents said predetermined voltage, E_d represents the voltage across said diode rectifier device when said diode rectifier device is conductive, and E_p represents the desired depressed collector voltage across said primary winding during operation of said traveling-wave tube.

12. A circuit for biasing a traveling-wave tube having a cathode, a slow-wave structure and a collector electrode for depressed collector operation comprising: power supply means for providing a predetermined voltage between first and second terminals, the positive terminal being connected to said slow-wave structure and the negative terminal being connected to said cathode, a pulse operated switch tube connected between said cathode and the negative terminal of said power supply means, a pulse transformer having a primary winding and a secondary winding, said primary winding having a large excitation inductance and being connected between said slow-wave structure and said collector electrode, a diode rectifier device having an anode terminal and a cathode terminal, said diode rectifier device and said secondary winding being connected in series between said first and second terminals with said cathode terminal facing the positive one of said first and second terminals, said transformer having an effective ratio of secondary turns N_s to primary turns N_p given by

$$\frac{N_s}{N_p} = \frac{E_{bb} + E_d}{E_p}$$

45 where E_{bb} represents said predetermined voltage, E_d represents the voltage across said diode rectifier device when said diode rectifier device is conductive, and E_p represents the desired depressed collector voltage across said primary winding during operation of said traveling-wave tube.
